COMBINED RAZOR BLADE AND HOLDER THEREFOR

David H. Arnold, Baytown, and Billy-Joe Leake, Sr.,
Houston, Tex., assignors, by direct and mesne assign-
ments, of one-tenth interest to William E. Ford, Hous-
ton, Tex.

Filed June 4, 1964, Ser. No. 80,279

Term of patent 14 years

(Cl. D95—3)

FIG. 1 is an isometric side, front and under edge view of our new design; and

FIG. 2 is an isometric side, rear and under edge view thereof, taken from the same side as the view of FIG. 1.

The other side is of corresponding appearance as the side shown, while the top edge view is substantially an elongated plane rectangle.

The dominant features of our design reside in the full line portions of the drawing.

The broken line showing of the handle has been omitted from FIG. 2 for convenience of illustration.

We claim:

The ornamental design for a combined razor blade and holder therefor, as shown and described.
